LOG SPLITTING GUN

Filed April 5, 1927

Fig. 1.

Inventor

Thorvald Berg

By Emery, Booth, James & Barney

Attorney

UNITED STATES PATENT OFFICE

THORVALD BERG, OF PORT ANGELES, WASHINGTON

LOG-SPLITTING GUN

Application filed April 5, 1927. Serial No. 181,207.

My invention aims to provide an improved gun for splitting logs by means of explosives, particularly adapted for splitting pulp wood.

5 Among the objects of this invention are to prevent deformation of the gun when repeatedly hammered into logs, to prevent entrance of water and dirt into the vent and to enable the vent to be readily cleaned or 10 renewed.

Further objects and advantages will be apparent to those skilled in the art from the following description and accompanying drawings, which illustrate a preferred embodiment of my invention, it being contemplated that the characteristic features of my invention may be applied in other forms than that shown and described.

In the accompanying drawings, 20 Fig. 1 is a longitudinal cross section; and Fig. 2 is a side view in perspective of my improved log splitting gun.

My splitting gun consists of a barrel comprising, successively, a tapered muzzle 12, a 25 cylindrical chase 13, a taper 14 to the breech portion, and a cylindrical breech portion 15.

The tapered muzzle increases rearwardly from a diameter slightly larger than that of the bore to the diameter of the cylindrical 30 chase 13, and the second conical portion or breech taper 14 is near the rear end of the chase, whereby the barrel is enlarged to the diameter of the breech portion 15.

The bore 16 of the gun extends back from 35 the muzzle about three-fourths of the length of the barrel, this type of gun being a muzzle-loader. Near the inner end of the bore a radial internally-threaded vent hole 17 communicates with the outside of the barrel. The 40 breech of the gun is bored from the rear towards the muzzle with a shallow recess 18 of relatively large diameter, a sufficient thickness of steel for safety being left between the inner end of the bore and the bottom of the recess.

A removable vent bushing 19, preferably of case-hardened steel, externally threaded, and centrally pierced with a vent hole 20 enlarged at the outer end 21 to receive the end 50 of a fuse, is screwed into the vent hole. This

bushing has an enlarged head 22 adapted to project above the outer surface of the barrel, and the breech portion 15 is flattened immediately behind the breech taper 14 to provide a seat 27 for the head 22.

55 A driving head 23 of hard wood, one end being of a diameter to fit the breech recess 18, the other end being enlarged, with shoulders 24 to fit the edge of the breech recess, is provided to take the blows of a hammer when the gun is driven into a log, thus preventing deformation of the metal. The rear end of this driving head is preferably reinforced by an iron band 25 to prevent splitting, while a set screw 26 or other suitable retaining means passing through a hole in the wall of the breech recess holds the driving head from falling out.

60 In operation, the gun is loaded from the muzzle with a powder charge and a wad, and is then driven into the log by a sledge hammer, after the manner of a wedge, with the vent preferably upward. The tapered muzzle 12 facilitates driving the barrel into a log, especially of soft wood, without first boring 65 a hole. The breech taper 14 and the protruding head 22 of the vent bushing 19 prevent water from the log, which may run along the chase, from entering the vent and wetting the powder charge. When the charge is 70 fired by a fuse inserted in the hole 21 the log is split by the force of the explosion, and the gun is freed therefrom.

75 The barrel is simple and strong, and nothing about it is easily broken or deranged. 80 The vent plug may be removed readily for cleaning or replacement and the wood head likewise may readily be replaced when battered from use.

Having described a preferred embodiment 85 of my invention, without restricting the invention thereto what I claim is as follows:

1. In a log splitting gun, in combination, 90 a barrel having a tapered muzzle, a cylindrical chase, a breech taper, an enlarged cylindrical solid breech, a removable driving head, a recess in said breech adapted to receive said driving head, a bore, a vent hole extending from said bore to the outer surface 95 of said breech cylinder, and a removable vent 100

bushing, one end of said bushing being adapted to project above the outer surface of said breech cylinder.

2. In a gun adapted to be hammered into wet logs, in combination, a tapered muzzle portion adapted, when driven in, to wedge apart the fibers of a log, a cylindrical chase adapted to engage said fibers without further wedging, an enlarged breech, an enlarged axial recess in the rear of said breech, a charge-receiving bore from said muzzle terminating in said breech, a vent hole from the rear of said bore to the surface of said breech, said breech enlargement being adapted to prevent the flow of water along the surface of said gun into said vent hole, and a driving head fitting the axial recess in said breech and projecting therefrom, said driving head being adapted to transmit the shock of hammer blows to said breech and protect said breech from being deformed thereby.

3. A log splitting gun adapted to be driven horizontally into a log, comprising, a shaft which is from muzzle to breech externally successively outwardly tapered, cylindrical, further tapered outwardly, and again cylindrical, an axial cylindrical bore therein extending from muzzle to within the second cylindrical portion, a lateral hole from the rear of said bore to the surface of said second cylindrical portion, a vent plug in said hole having an external head elevated above the surface of said second cylindrical portion, a larger relatively shallow bore from the rear of said second cylindrical portion, a solid wall between the bottoms of the two said bores, and an impact receiving plug within said second bore.

4. A log splitting gun adapted to be driven horizontally into a log, comprising, a shaft which is from muzzle to breech externally successively outwardly tapered, cylindrical, further tapered outwardly, and again cylindrical, an axial bore therein extending from muzzle to within the second cylindrical portion, a larger relatively shallow bore from the rear of said second cylindrical portion, a solid wall between the bottoms of the two said bores, and an impact receiving plug within said second bore.

In testimony whereof, I have signed my name to this specification.

THORVALD BERG.
